UNITED STATES PATENT OFFICE.

CHARLES A. CONRAD, OF BROOKLYN, NEW YORK.

PIN-TAG.

1,127,862.

Specification of Letters Patent.

Patented Feb. 9, 1915.

Application filed December 18, 1913. Serial No. 807,506.

To all whom it may concern:

Be it known that I, CHARLES A. CONRAD, a citizen of the United States, residing at Brooklyn, in the county of Kings and State 5 of New York, have invented certain new and useful Improvements in Pin-Tags, of which the following is a full, clear, and exact specification.

This invention relates to tags, and has for 10 its object to provide means for attaching the tag to cloth or other articles without danger of scratching or piercing the fingers, either in attaching the tag or in handling the cloth or article after the tag is attached 15 to the same.

Another object is to provide means for attaching the tag very quickly to the article desired and in such manner that it will not become accidentally detached although it 20 may be readily taken off when necessary or it is desired to use it again.

The invention is designed especially for use in marking clothing or garments, but it is obvious that it may be employed in many 25 other places to advantage.

The invention will be first hereinafter described in connection with the accompanying drawings, which constitute a part of this specification, and then more specifically 30 defined in the claim at the end of the specification.

In the accompanying drawings, wherein similar reference characters are used throughout the several views to designate 35 corresponding parts:—Figure 1 is a front view of a tag made in accordance with my invention. Fig. 2 is an edge view showing the pin hooks open, as when the tag is to be attached to a garment or the like. Fig. 3 40 is an edge view showing the pin hooks closed into the form of an eye, as is done after attachment in order to prevent accidental detachment and the scratching or piercing of the fingers. Fig. 4 is a rear view of the tag. 45 Fig. 5 is a front view thereof, showing how the hooks may be turned around into the plane of the tag or card after attachment to a garment or the like, and Fig. 6 is a perspective view of the tag with the pin hooks 50 open, as they are supplied to the trade.

Referring more particularly to the drawings, A designates the pin hook or fastening device, which is preferably made of a single piece of wire bent upon itself to form 55 two parallel members which are passed through the upper portion of the card B at

a. The middle or looped portion a' of the fastener is bent over the upper edge of the card, as clearly illustrated, in order to hold said fastener rigidly or against turning on the card. The end portions of the wire are bent into the form of parallel pin hooks a² having pointed ends or extremities a³ which normally are inclined slightly outward, as best illustrated in Figs. 2 and 6. By reason 60 of this normal inclined position of the pointed extremities of the pin hooks, they may be readily hooked into the garment or other article while grasping the card, it being unnecessary to touch the pins with the 65 fingers in order to accomplish this first step in the operation of attachment. After the hooks have been passed through the article, the pointed extremities of the hooks may be bent into the form of eyes, or closed, as 70 illustrated in Fig. 3, by pressing upon the rounded looped portions of said hooks adjacent their pointed extremities without touching said points themselves. Thus, it 75 will be seen that it is unnecessary to bring 80 the fingers into contact with the points of the fastening device in either step of the attaching operation, so that there is no danger of scratching or piercing the fingers. Either before or after the hooks have been 85 closed into eyes, they may be turned around, preferably in opposite direction as illustrated in Fig. 5, so as to bring them into the plane of the card B and leave no protuberances on the surface of the garment or 90 other article.

It will be noted that while there is no danger of the pin hooks becoming disengaged from the article to which they are attached, when not desired, yet they may 95 be easily opened from closed or the eye-shaped position in order to permit the tag to be removed when necessary or it is desired to use said tag over again. In thus opening the hooks, they may be grasped at 100 their looped portions, so that even in the operation of removing the tag, there is no occasion for touching the points of the hooks with the fingers.

Having thus described my invention, what 105 I claim as new and desire to secure by Letters Patent of the United States is:—

A tag comprising a card and a fastening device made of a single piece of wire passed through the margin of the card and having 110 pointed hook-shaped projections which are rounded in contour, having wide rounded

bends extending beyond the plane of the side of the card on which the points are arranged, the pointed extremities of each hook-shaped projection terminating beyond 5 the edge of the card and extending in an inclined position with respect to the plane of the card away from said plane prior to attachment of the tag to an article of merchandise, said extremities, by reason of the 10 wide bends projecting beyond the plane of the card, being adapted to be bent to an inwardly inclined position with the points in the plane of the card after attachment,

whereby the points are entirely out of the way of accidentally being engaged by the 15 fingers of persons handling the article of merchandise to which the tag is thus attached.

In testimony whereof I have signed my name to this specification in the presence of 20 two attesting witnesses.

CHARLES A. CONRAD.
